CLAIM

The ornamental design for a set of dice, substantially as shown and described.

DESCRIPTION

FIG. 1 is a perspective view taken from the front, upper and right side of a first die of a set of dice in accordance with this invention, showing the top, front and left face thereof.

FIG. 2 is a perspective view taken from the back, lower and left side thereof and showing the bottom, rear and right face thereof.

FIG. 3 is a perspective view taken from the front, upper and right side of a second die showing the top, front and left face thereof.

FIG. 4 is a perspective view taken from the back, lower and left side of the second die and showing the bottom, rear and right face thereof.

FIG. 5 is a perspective view taken from the front, upper and right side of a die of a third die showing the top, front and left face thereof; and,

FIG. 6 is a perspective view taken from the back, lower and left side of the third die and showing the bottom, rear and right face thereof.
